DOUBLE ACTING PUMP

Harry P. Anderson and Frederick L. Johnstone,
Detroit, Mich.

Application May 16, 1940, Serial No. 335,456

6 Claims. (Cl. 103—195)

This invention relates to new and useful improvements in a pumping mechanism for use in pumping liquids of different consistencies, such as water with relatively small effort, or heavy liquids or oils requiring greater effort.

The invention also lends itself very efficiently to pumping liquids contaminated with solid particles in suspension, such as grit, abrasives, or metal particles, frequently encountered in handling waste oils and liquids.

The primary object of the invention is the design of a pumping mechanism so arranged and constructed as to eliminate various ball checks and seats with which most pump failures and decreased efficiency of operation are associated.

Another object of the invention is the provision of a double acting pump of the class described having a minimum of working parts and surfaces, resulting in a pumping device of greater efficiency and durability.

Another object resides in the provision of an intermediate pressure supply chamber between the source of supply and the ultimate point of delivery of the fluid being pumped with a consequent effecting of more even delivery of fluid.

Another object of the invention resides in so designing a pump mechanism that it is compact and economical of manufacture.

Other objects will appear hereinafter as the description is understood.

With reference to the accompanying drawings which form a part of this specification, like reference characters refer to similar parts throughout the several views in which.

Fig. 1 is an elevation of the invention showing it mounted in a reservoir or the like, with a portion broken away, and

Fig. 2 is a vertical sectional view taken upon line 2—2 of Fig. 1, showing the piston preparatory to the downward stroke, and

Fig. 3 is a view similar to Fig. 2, with the piston near its lower position, and

Fig. 4 is a transverse sectional view taken upon line 4—4, of Fig. 3, and

Fig. 5 is a transverse sectional view taken upon line 5—5 of Fig. 3.

In the drawings the device is shown as comprising a cylindrical shell 5, having an inner bore or chamber 7 and at its upper end is secured a closure casting 9 provided with apertures for a suitable discharge pipe 11 and another for a conventional packing gland thru which a piston rod hereinafter to be described protrudes.

Threadedly mounted to the bottom of the shell 5 is the base casting 13, having an axial bore 15, 55

into which a piston or plunger 17 extends. The piston being of a greater length than the bore 15, partially extends into the chamber 7, being adapted to reciprocate partially in said chamber and partially in the bore 15 of the casting 13 for the intake and discharge of the fluid being pumped.

Horizontal ports 19 and 21 are formed in the base 13 for the inflow of fluids from the source of supply in which the device is immersed, and a suitable plug 23 is mounted in the base to close the lower end of the bore 15.

Referring more particularly to the piston 17, it is provided with an inner bore 25, having an enlarged counterbored portion 25A for ease and cheapness of manufacture, eliminating the necessity of grinding throughout the entire bore. The upper portion of the bore is also reduced as at 25B for a purpose to be hereinafter described.

20 A secondary piston or plunger 27 is adapted to reciprocate within said bore 25, 25A and 25B of the piston 17, having close sliding contact with the portion designated by the numeral 25. The piston 27 has a central axial fluid passage 29, 25 which communicates with the bore 15 in the base. The upper end of the passage is sealed by one 30 end of a piston rod 31 threadedly mounted therein. An adjustment nut 33 is provided on the piston rod 31 for a purpose to be hereinafter described.

At their upper ends, both pistons are provided with horizontal discharge ports 35 and 37, serving to conduct fluid into the chamber 7 of the shell 5 upon descending stroke of the two pistons previously described.

The piston 27 may be provided with a reduced middle external portion for ease in manufacture, reducing frictional contact, leaving a substantial lower portion for sealing contact between the two pistons.

45 The upper portion of piston 27 is considerably reduced as shown at 28, forming a shoulder 28a for contacting a shoulder 25c in the bore of piston 17.

The upper portion of piston 27 is considerably reduced as shown at 28, forming a shoulder 28a for contacting a shoulder 25c in the bore of piston 17.

Operation

Referring to Fig. 2, it will be noted that the pistons are in their uppermost positions and the ports 35 and 37 are not in registry.

50 In coming to this position, the piston 27 first moved the distance corresponding to the distance that shoulders 28a and 25c are shown apart in Fig. 3, the two shoulders then abutting, and this action closed the ports 35 and 37. Thereafter the two pistons 27 and 17 moved upwardly as a unit,

The upward motion of the pistons thus created a vacuum in the bottom of the chamber 15, permitting atmospheric pressure as well as the weight of the liquid to force liquid into said chamber through the ports 19 and 21, as indicated by the arrows in Fig. 2.

As the pistons 17 and 27 rise in chamber 7, they displace a volume of liquid therefrom equal to the volumetric area of the travel of the pistons, pumping the same out the outlet pipe 11.

Upon the descending stroke of the piston rod 31, the piston 27 will first descend until the nut 33 engages the upper surface of piston 17, at which time the ports 35 and 37 will register, as shown in Fig. 3. Thereafter the two pistons will descend as a unit, closing ports 19 and 21 and discharging the fluid that was previously trapped in the lower part of chamber 15, through axial passage 29 of inner piston 27 and out through ports 35 and 37 into the chamber 7 in shell 5, and thence forcing some fluid out through discharge pipe 11.

The parts are so designed that the volume of liquid trapped in the lower portion of chamber 15 is greater than the volume displaced by the upward stroke of the pistons, so that some fluid is pumped out of the discharge pipe 11 upon movement of the pistons in each direction.

Aside from the specific embodiment of the invention herein shown and described, it will be understood that numerous details of the construction may be altered or omitted without departing from the spirit and scope of the invention as disclosed and claimed, and that we do not desire to limit the invention to the exact construction herein set forth.

We claim:

1. A pump comprising a large cylinder, a smaller cylinder mounted in one end thereof provided with a fluid inlet, a hollow outer piston mounted in sealing relation in the smaller cylinder and adapted to reciprocate partially in each cylinder, a hollow inner piston mounted in the hollow outer piston and closed at one end, a lost motion connection between said pistons, means for reciprocating said inner piston and thereby ultimately reciprocating the outer piston through said connection, ports in said inner and outer pistons adapted to register for discharging fluid therethrough into the large cylinder when said inner piston has been moved sufficiently in one direction to take up the lost motion between the pistons and adapted to be out of registry when said inner piston moves in the opposite direction, and a discharge port leading from said large cylinder.

2. A pump comprising a large cylinder, a smaller cylinder mounted in one end thereof provided with a fluid inlet, a hollow outer piston mounted in sealing relation in the smaller cylinder and adapted to reciprocate partially in each cylinder, a hollow inner piston mounted in the hollow outer piston and closed at one end, a lost motion connection between said pistons, means for reciprocating said inner piston, said reciprocating means, on each stroke, first causing the lost motion to be taken up and then causing the connection to become effective to thereafter move the outer piston with it as a unit during the remainder of said stroke, ports in said inner and outer pistons adapted to register for discharging fluid therethrough into the large cylinder when said inner piston has been moved sufficiently in one direction to take up the lost motion between the pistons and adapted

to be out of registry when said inner piston moves in the opposite direction, and a discharge port leading from said large cylinder.

3. A pump comprising a large cylinder, a smaller cylinder mounted in one end thereof provided with a fluid inlet, a hollow outer piston mounted in sealing relation in the smaller cylinder and adapted to reciprocate partially in each cylinder, a hollow inner piston mounted in the hollow outer piston and closed at one end, a piston rod for reciprocating said inner piston, a lost motion connection between said pistons, including an outer shoulder on the inner piston and an inner shoulder on the outer piston and a projection on said piston rod, said piston rod, on each stroke, first moving the inner piston sufficiently to take up the lost motion, thus causing the connection to become effective to thereafter move the outer piston with the inner piston during the remainder of said stroke, ports in said inner and outer pistons adapted to register for discharging fluid therethrough into the large cylinder when said inner piston has been moved sufficiently in one direction to take up the lost motion between the pistons and adapted to be out of registry when said inner piston moves in the opposite direction, and a discharge port leading from said large cylinder.

4. A pump mechanism of the class described comprising; a large cylinder having a discharge outlet, a smaller cylinder mounted in one end of said large cylinder and provided with a fluid inlet, a hollow outer piston mounted in sealing relation in the smaller cylinder, adapted to reciprocate partially in each cylinder and having ports communicating with the large cylinder, an inner piston mounted in the hollow outer piston, said inner piston having a longitudinal bore closed at one end, ports passing through the upper end of said inner piston for delivery of fluid from the smaller cylinder through the longitudinal bore of said inner piston to the bore of the outer piston, means for reciprocating said inner piston, and a lost motion connection between said pistons including an external shoulder on said inner piston at a point substantially below its ports, an internal shoulder in the hollow outer piston in alignment with the top of its ports, said shoulders being adapted to contact each other when the piston ports are out of registry, a projection on the reciprocating means adapted to contact the first named piston when the piston ports are in registry, whereby, upon the downward stroke of the inner piston it will first descend until the piston ports are in registry, at which time the projection on the reciprocating means will engage the outer piston and the two pistons will then descend as a unit, closing the inlet means in the smaller cylinder and discharging the trapped liquid through the bore of the inner piston and through the registering piston ports into the large cylinder, thereby discharging some of the liquid out of the discharge outlet and, upon the upward stroke of the inner piston, it first moves up to place the piston ports out of registry and, when the external shoulder of said inner piston contacts the inner shoulder of the first named piston, the two pistons will continue to move upwardly as a unit, thereby creating a vacuum in the smaller cylinder until the outer piston uncovers the fluid inlet in the smaller cylinder, at which time liquid in the source of supply will flow into the smaller cylinder, the upward movement of the pistons simultaneously displacing a volume of liquid

from the large cylinder and out through the discharge outlet.

5. A pump mechanism of the class described comprising; a shell having an inner chamber, a top closure for said shell and outlet means leading from said shell, a base affixed to said shell, a cylindrical bore in said base, inlet means for conducting fluid into said bore, a piston adapted to reciprocate in said bore, said piston having a central bore formed therein and fluid ports communicating with the shell chamber, an inner piston mounted in said central bore of the first named piston and adapted to partially slide therein and to partially reciprocate with said first named piston, said inner piston having a longitudinal passageway, ports in the upper end of said inner piston connecting with said passageway for delivery of fluid from the cylindrical bore in the base to the bore of the first named piston, means for reciprocating said inner piston, said inner piston having an external shoulder at a point substantially below its ports, an internal shoulder in the bore of said first named piston in alignment with the top of its ports, said shoulders being adapted to contact each other when the piston ports are out of registry, a projection on the reciprocating means adapted to contact the upper surface of the first named piston when the piston ports are in registry, whereby, upon the downward stroke of the inner piston it will first descend until the piston ports are in registry, at which time the projection on the reciprocating means will engage the upper surface of the first named piston and the two pistons will then descend as a unit, closing the inlet means to the bore in the base and discharging the trapped liquid through the longitudinal passage in said inner piston through the registering piston ports into the shell chamber, thereby discharging some of the liquid out of the outlet means and, upon the upward stroke of the inner piston, it first moves up to place the piston ports out of registry and, when the external shoulder of said inner piston contacts the inner shoulder of the first named piston, the two pistons will continue to move upwardly as a unit, thereby creating a vacuum in the lower bore of the base until the first named piston uncovers the inlet means in the base at which time liquid in the source of supply will flow into the bore of said base, the upward movement of the pistons simultaneously displacing a volume of liquid from the shell chamber and out through the outlet means.

6. A pump mechanism of the class described

comprising; a shell having an inner chamber, a top closure for said shell and outlet means leading from said shell, a base affixed to said shell, a cylindrical bore in said base, inlet means for 5 conducting fluid into said bore, a piston adapted to reciprocate in said bore, said piston having a central bore formed therein and fluid ports communicating with the shell chamber, an inner piston mounted in said central bore of the first named piston and adapted to partially slide therein and to reciprocate with said first named piston, said inner piston having a longitudinal passageway, ports in the upper end of said inner piston connecting with said passageway for delivery of fluid from the cylindrical bore in the base to the bore of the first named piston, a piston rod secured to said inner piston for reciprocating said piston and projecting through said top closure, said inner piston having an external shoulder at a point substantially below its ports, an internal shoulder in the bore of said first named piston in alignment with the top of its ports, said shoulders being adapted to contact each other when the piston ports are out of registry, a nut on the piston rod adapted to contact the upper surface of the first named piston when the piston ports are in registry, whereby, upon the downward stroke of the piston rod, the inner piston will first descend until the piston ports are in registry at which time the nut on the piston rod will engage the upper surface of the first named piston and the two pistons will then descend as a unit, closing the inlet means to the bore in the base and discharging the trapped liquid through the longitudinal passage in said inner piston through the registering piston ports into the shell chamber, thereby discharging some of the liquid out of the outlet means and, upon the upward stroke of the piston rod, the inner piston first moves up to place the piston ports out of registry and, when the external shoulder of the inner piston contacts the inner shoulder of the first named piston, the two pistons will continue to move upwardly as a unit, thereby creating a vacuum in the lower bore of the base until the first named piston uncovers the inlet means in the base at which time liquid in the source of supply will flow into the bore of said base, the upward movement of the pistons simultaneously displacing a volume of liquid from the shell chamber and out through the outlet means.

HARRY P. ANDERSON.
FREDERICK L. JOHNSTONE.
